UNITED STATES PATENT OFFICE.

CHARLES STRATHMANN, OF NEW YORK, N. Y.

DESIGN FOR A SIGNAL-LAMP.

54,789.

Specification for Design.

Patented Mar. 23, 1920.

Application filed November 15, 1919. Serial No. 338,389. Term of patent 14 years.

To all whom it may concern:

Be it known that I, CHARLES STRATHMANN, a citizen of the United States, and a resident of the borough of Manhattan, city, county, and State of New York, have invented a new, original, and ornamental Design for Signal-Lamps, of which the following is a specification, reference being had to the accompanying drawing, forming part thereof.

The figure is a perspective view of a signal

lamp embodying my new design. The signal words indicated by way of example in the drawing, may be varied without departing from my invention, the essence of which resides in the general appearance of the signal lamp substantially as shown.

I claim:

The ornamental design for a signal lamp substantially as shown.

CHARLES STRATHMANN.
